DESIGN FOR AN ANDIRON.

SPECIFICATION forming part of Design No. 36,048, dated September 9, 1902.

Application filed July 29, 1902. Serial No. 117,568. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Andirons, of which the following is a full, clear, and exact description, reference being had to the accompanying drawing, forming part hereof, in which is represented a pair of andirons duplicates of each other and each embodying the design.

The leading features of the design consist of a body portion having generally a bat-like appearance. Extending from the body portion, above the head, is a standard or upright having a roughened appearance and topped off with an enlargement having thereon oppositely-extending scrolls. Extending from the tips of the wings are claws holding balls, which form the feet of the andiron, the back support thereof being constituted of an angled bar extending from the body of the andiron.

I claim—

The ornamental design for an andiron as herein shown and described.

In testimony whereof I hereunto set my hand in the presence of two subscribing witnesses.

THOMAS M. DUDGEON.
